UNITED STATES PATENT OFFICE.

KARL ALQUIST, OF SCHENECTADY, NEW YORK, ASSIGNOR TO GENERAL ELECTRIC COMPANY, A CORPORATION OF NEW YORK.

MARINE TURBINE.

1,153,475.

Specification of Letters Patent. Patented Sept. 14, 1915.

Application filed January 20, 1915. Serial No. 3,254.

To all whom it may concern:

Be it known that I, KARL ALQUIST, a subject of the King of Sweden and Norway, residing at Schenectady, county of Schenectady, State of New York, have invented certain new and useful Improvements in Marine Turbines, of which the following is a specification.

The present invention relates to turbines 10 for propelling vessels, and in particular to those intended for war vessels which, for the greater part of the time, are operating at cruising speed, but are at times required to operate at higher or maximum speeds.

15 The purpose of my invention is to provide an arrangement or grouping of turbines for propelling a vessel, and in particular one having twin screws or propellers, which, by changing the number of turbines in service and the manner in which they receive steam or other elastic motive fluid, can be made to operate with high economy at maximum, intermediate, and cruising speeds.

20 25 For a consideration of what I believe to be novel and my invention, attention is directed to the accompanying description and claims appended thereto.

In the accompanying drawing which is 30 illustrative of my invention, Figure 1 is a diagrammatic view in plan of a twin-screw system of turbine propulsion for vessels; Fig. 2 is a diagrammatic illustration of a main and a cruising turbine; Fig. 3 is a diagrammatic detail view of the main and auxiliary nozzles; Fig. 4 is a detail view of a double seated valve for controlling the admission of steam to the main and cruising turbines, and Figs. 5 to 7 are diagrammatic views 35 illustrating the flow of steam to the turbines under different operating conditions.

2 and 3 indicate twin main turbines for propelling the vessel at maximum speed, each of which drives a propeller shaft 4 either directly or through speed reducing gearing 5. The latter arrangement is preferable because the propeller 6 can be driven at its most favorable effective speed, while the turbine can be made relatively 45 small and light and operated at a high and most favorable speed, thereby obtaining good economy of operation. By arranging the gearing in the position shown it is always in service whether the ship is being driven at full, intermediate or cruising 50 55

speed. I have not illustrated the gearing in detail because its specific construction forms no part of the present invention. In other pending applications I have disclosed gearing suitable for this purpose. The turbines 60 operate on the impulse plan and are preferably of the Curtis type because of their high economy and decreased weight and moderate speed for a given output. Each turbine has a forward driving element 7, 65 Fig. 2, comprising in the present instance one or more wheels 8 having a plurality of rows of peripheral buckets and one or more wheels 9, each having a single row of peripheral buckets, said wheels being mounted 70 on the shaft 10. In the rear end of each turbine casing is located a reversing element 11 comprising one or more bucket wheels mounted on the shaft 10. Both the forward driving and reversing elements 75 exhaust into condensers 12. The extracting capacity of turbine buckets depends roughly on the square of their speed. That is to say, if the bucket speed be decreased one-half the energy range for equal extracting 80 efficiency thereof will be reduced to about one-fourth, hence the importance of increasing the number of stages for reduced speed operation, a feature which will be referred to later.

85 Each main turbine is provided with a set of nozzles 13 adapted in size and shape to receive high pressure boiler steam from the supply main 14 and convert a predetermined percentage of its pressure into velocity, which in turn is converted into useful work by the rotating element, as is well understood. Between the various bucket wheels, each in a stage of its own, are stage nozzles 90 95 15 for converting pressure into velocity and conveying steam between the stages in a manner well understood. Each turbine is also provided with an auxiliary or low pressure set of nozzles 16 adapted in shape and size to receive exhaust steam from a cruising 100 turbine, to be described later, and convert a predetermined percentage of its pressure into velocity, which in turn is converted into useful work by the rotating element. The main and auxiliary nozzles receive their 105 supplies of steam from separate chests, the purpose of which will be referred to later. When operating at full speed and power the auxiliary set of nozzles 16 in each main turbine is cut out of service. They are, 110

however, in service for cruising speed conditions. For full and high intermediate speed conditions the main admission nozzles only are in service. The main turbines are designed to give their maximum economy at nearly full or full speed of the ship.

Situated in line with the main turbines, and preferably forward thereof to facilitate cutting the same into and out of service, are auxiliary or cruising turbines 17 and 18 that are adapted to be connected to and disconnected from the main turbine shafts by releasable clutch couplings 19 and 20. These turbines are provided with bucket wheels of such diameter as to efficiently extract energy from the steam at lower speeds of the ship. They may be uncoupled from the main turbines when the latter are operating at high speed so as to avoid the rotation losses due to the rotation of the wheels within their casings. By uncoupling the cruising turbines when driving the vessel at highest speeds, I can make their bucket speeds somewhat higher than would otherwise be possible, though it is generally desirable to have the bucket strong enough to withstand the highest speed they would reach if the turbines were not disconnected. The cruising turbines have high pressure admission nozzles 21 adapted to convert a predetermined percentage of pressure into velocity which in turn is extracted by the buckets of the rotor. They exhaust into the separate auxiliary nozzles 16 of the main turbines and are adapted to extract only a portion of the total energy of the steam at any time. If the same nozzles were used in the main turbine for boiler steam and also for exhaust steam from the cruising turbine, whenever boiler steam was admitted to the chest supplying said nozzles it would also flow back into the shell of the cruising turbine and in this manner subject it to very high stresses. This could be avoided by using a valve in the conduit between the two shells but there would still be the danger of the operator neglecting to close it which is avoided by my improved construction. Further it would require an additional operation which I avoid. One of the cruising turbines is also provided with an auxiliary or low pressure set of nozzles 18, resembling the other nozzles in general construction, which is put into service only for low speed cruising conditions when the two turbines are serially arranged as regards the passage of steam, as will appear later in connection with Fig. 7. When the cruising turbines are operating in series as regards the passage of steam the main turbines are connected in parallel as regards the passage of steam, the various groups of admission and stage nozzles being proportioned in a manner well understood to give the desired work division.

High pressure or boiler steam is admitted to the main turbines in parallel for high speed propulsion by the conduit 14 subject to the control of throttle valves 23 and 24. High pressure or boiler steam is admitted to the auxiliary or cruising turbines by the conduit 14 subject to the control of the throttle valves 26 and 27. The exhaust steam from the cruising turbines 17 and 18 enters the main turbines 2 and 3 by the conduits 28 and 29 subject to the control of valves 30 and 31. Valve 30 may with advantage be of the construction shown in Fig. 4. The valve is of the double seat type and is operated by the usual nut and screw 32, there being a hand wheel 33 on the valve spindle. When the valve is raised all the steam passes to the main turbine and when lowered it all passes to the cruising turbine. By using a valve of this character one of the exhaust pipes always remains open and thus prevents any abnormal rise of pressure in the shell of the cruising turbine 17. It also enables me to reduce the total number of the valves required.

In Fig. 5 is shown diagrammatically the relation of parts for high speed operation of the vessel, for example 25 to 30 knots. The cruising turbines are mechanically disconnected from the main turbines by opening the clutches 19 and 20 and all steam is shut off therefrom by closing the supply valves 26 and 27. The auxiliary nozzles 16 of the main turbines are also inactive and valves 30 and 31 are shut. High pressure steam is admitted to both turbines in parallel from the main 14, the throttle valves 23 and 24 being open to the desired extent.

In Fig. 6 is shown diagrammatically the relation of parts for medium or intermediate speeds of the vessel. In this figure the main and cruising turbines are operating together, the parts of the clutch couplings 19 and 20 being united. High pressure steam is admitted in parallel to the starboard and port turbines, the exhaust from the cruising turbines passing through the conduits 28 and 29 to auxiliary sets of nozzles 16 into the main turbines, the latter exhausting into the condensers. This arrangement is adapted to operate at its best efficiency for an intermediate speed of the vessel of, say 20 knots.

In Fig. 7 is shown diagrammatically the relation of parts for low speed or cruising operation of the vessel. In this figure the cruising turbines are connected in series as regards the passage of steam, and the two main turbines are connected in parallel as regards the passage of steam, both operating on the exhaust steam from the cruising turbines. This arrangement is adapted for low speeds of the vessel, say 12 to 16 knots for example. Under this condition of operation the valve 30 will shut off the flow of steam from cruising turbine 17 to main

turbine 2 and cause all of it to pass through the conduit 34 to the auxiliary nozzles 18^a of the cruising turbine 18. After performing work in said turbine, the steam passes 5 through valve 31 where it divides, one-half going to the auxiliary or low pressure nozzles 16 of the main turbine 2 by conduit 35, and the remainder to the auxiliary or low pressure nozzle 16 of the second main turbine 3. Under these conditions the valve 31 occupies a mid position.

As an illustration of my invention, but not as a limitation thereof, the following 10 outputs and speeds may be considered as typical of the conditions for each propeller:

Knots.	Horse power.	Propeller revolutions per minute.
30	10,000	480
25	5,000	370
20	1,800	290
16	900	230
12	350	170

25 The illustration above given clearly shows the very great difference in shaft horse power between a vessel operating at maximum speed and the same vessel operating at low or cruising speeds. It also makes apparent 30 the very great necessity of so arranging or combining the turbines in different ways or groups so that they can economically utilize the motive fluid at different speeds of the vessel. My improved arrangement 35 contemplates three principal speeds of the vessel—high, intermediate, and low, at which a high degree of economy in the use of steam or the motive fluid is effected, these being sufficient for the great majority of 40 cases. For speeds other than those specified I can resort to cutting nozzles out of service, as by the valves 36, especially for the main turbines, or by throttling the supply of steam. As a general proposition the feature 45 of cutting nozzles into and out of service will be limited to the high pressure portions of the installation and throttling to the low pressure portions, although in some instances either or both modes of control may 50 be employed.

The principal advantage of my improved arrangement resides in the fact that the vessel can be operated economically at the three speeds most often required, thereby 55 increasing its radius of operation. This primary advantage is brought about by the fact that the main turbines with their main admission nozzles can be designed to give their best efficiency at high speeds, that for intermediate speeds additional and efficient turbines can be put into service so that a greater number of wheels or rows of buckets can be employed whereby they will have substantially 60 the same total extraction efficiency, but 65 at a lower speed with a lower total steam

volume. This is in part due to the use of auxiliary nozzles which are properly designed to handle the volume of steam received from the cruising turbines. For low vessel speeds a still greater number of turbines 70 wheels are arranged in series as regards the passage of steam and hence a lower speed of the vessel is obtained with a corresponding lower shaft speed and a decrease in total steam volume without substantial sacrifice in 75 economy of operation.

By employing cruising turbines arranged in the manner described I reduce the losses when the vessel is operating at full speed because the cruising turbines do not form a 80 dead load on the main turbines, and I may further avoid the danger due to operating said turbines under greater speeds than they are designed for, and because of this turbines of less expensive construction may be 85 used.

In accordance with the provisions of the patent statutes, I have described the principle of operation of my invention, together with the apparatus which I now consider to 90 represent the best embodiment thereof; but I desire to have it understood that the apparatus shown is only illustrative, and that the invention can be carried out by other means.

What I claim as new and desire to secure 95 by Letters Patent of the United States, is:—

1. In a system of ship propulsion, the combination of main turbines arranged to propel the ship at maximum speed, cruising turbines arranged to coöperate with the 100 main turbines to propel the ship at speeds below the maximum, and means arranged to connect the cruising turbines in series with the main turbines as regards the flow of steam for intermediate speed conditions and 105 to connect the cruising turbines serially as regards the flow of steam and to supply the exhaust therefrom to the main turbines in parallel for lower speeds of the ship.

2. In a system of ship propulsion, the combination of propeller shafts, main turbines arranged to propel the ship at maximum speeds, speed reducing gearing between the turbine and propeller shafts, 110 cruising turbines arranged to be connected to the main turbines and coöperate therewith to propel the ship at speeds below the maximum, releasable couplings between the shafts of the main and cruising turbines, and means arranged to connect the cruising 115 turbines in series with the main turbines as regards the flow of steam for intermediate speeds of the ship and to connect the cruising turbines serially as regards the flow of steam and to supply the exhaust therefrom 120 to the main turbines in parallel for lower speeds of the ship.

3. In a system of ship propulsion, the combination of main turbines arranged to 125 propel the ship at maximum speed, main and 130

- auxiliary nozzles for the turbines, the former being adapted in size and shape to receive live steam and the latter exhaust steam, cruising turbines arranged to coöperate with 5 the main turbines to propel the ship at speeds below the maximum, means arranged to deliver the exhaust from the cruising turbines in parallel to the auxiliary nozzles of the main turbines for intermediate speed conditions, and means arranged to connect the 10 cruising turbines serially as regards the flow of steam and to supply the exhaust therefrom to the auxiliary nozzles of the main turbines in parallel for lower speeds of 15 the ship.
4. In a twin screw system of ship propulsion, the combination of twin propeller shafts, two main turbines for driving the ship at full speed, speed reducing gearing 20 between each turbine and its corresponding propeller shaft, two cruising turbines, releasable couplings for connecting the shafts of the cruising turbines to those of the main turbines, and means for connecting the 25 cruising turbines in series as regards the flow of steam with the main turbines for certain speeds of the ship and for connecting them in series as regards the flow of steam and to exhaust into the main turbines for certain 30 other speeds of the ship.
5. In a system of ship propulsion, the combination of propeller shafts, main turbines coupled thereto for propelling the ship at maximum speed, cruising turbines each having 35 a separate casing and whose rotor is coupled to the respective main turbine shaft for cruising speeds, all of said turbines being provided with nozzles so proportioned as to give the desired work division, means 40 for connecting the cruising turbines to and disconnecting them from the main turbines, conduit means for connecting each cruising turbine in series with a main turbine and for connecting the cruising turbines in series 45 with each other as regards the flow of motive fluid and to exhaust into both main turbines, and valves in said conduit means for controlling the passage of motive fluid therethrough.
6. In a system of ship propulsion, the 50 combination of propeller shafts, condensing main turbines coupled thereto for propelling the ship at maximum speed, cruising turbines having separate casings whose rotors are in line with the shafts of the main turbine and are coupled thereto for low speeds only of the ship, all of said turbines being provided with nozzles so proportioned as 55 to give the desired work division, releasable couplings between the main and cruising turbines, conduits for admitting live steam to the main turbines for high speeds and to the cruising turbines for lower speeds, a conduit connecting the exhaust of one cruising 60 turbine with the inlet of another, conduits for connecting the exhaust of the last named cruising turbine with the low pressure nozzles of the main turbines, and valve means controlling the passage of steam through the conduits. 65
7. In a system of ship propulsion, the combination of propeller shafts, condensing main turbines coupled thereto for propelling the ship at maximum speed, main and auxiliary nozzles for said turbines, cruising turbines having separate casings whose rotors are coupled to the main turbine shafts for 70 low speeds only of the ship, main nozzles for the cruising turbines, an auxiliary nozzle for one of said turbines, the nozzles of all of 75 said turbines being so proportioned as to give the desired work division, releasable couplings between the main and cruising turbines, conduits admitting live steam to the turbines, a conduit for connecting the 80 exhaust of one cruising turbine with the auxiliary nozzle of another cruising turbine, conduits receiving the exhaust of the last named turbine and delivering it to the auxiliary nozzles of the main turbines, and valve means for controlling the passage of steam through the conduits. 85
- In witness whereof, I have hereunto set my hand this 13th day of January, 1915.
- KARL ALQUIST.
- Witnesses:
- HELEN ORFORD,
MARGARET E. WOOLLEY.
